UNITED STATES PATENT OFFICE.

HOWARD M. LEONARD, OF SOUTH BEND, INDIANA, ASSIGNOR TO BENDIX BRAKE COMPANY, OF CHICAGO, ILLINOIS, A CORPORATION OF ILLINOIS.

BRAKE.

Application filed March 7, 1927. Serial No. 173,245.

- This invention relates to brakes, and is illustrated as embodied in an internal expanding brake of the type having three floating shoes arranged end to end within the drum.
- 5 Various features of novelty relate to applying means including a pair of levers acting on two of the shoes (or on equivalent friction means) and one of which operates a third lever, to novel torque-taking devices arranged 10 to wedge the shoes against the drum, to a new form of applying or expanding cam, and to other novel and desirable particular constructions which will be apparent from the following description of the illustrative embodiment shown in the accompanying drawing, in which:
- 15 Figure 1 is a vertical section through the brake, just inside the head of the brake drum, and showing the brake shoes in side elevation; 20 and
- 20 Figure 2 is a partial section on the line 2—2 of Figure 1, showing the spring arrangement.
- 25 The brake includes generally a rotatable drum 10, at the open side of which is the usual backing plate or other support 12, and within which is arranged the friction means, which is shown as including three floating interchangeable shoes 14, 16, and 18, each approximately 120° in length, arranged end to end.
- 30 At each end of each shoe is a double-wedge recess 20 facing toward the center of the drum, and within each recess there is a part such as a roller 22 mounted on the backing plate 12. Rollers 22 have three functions:
- 35 (1) they position the shoes when the brake is released; (2) they take the braking torque; and (3) they wedge the shoes against the drum as they tend to turn with the drum when 40 the brake is applied.
- 40 Shoe 14 is connected directly at its right end to the lower end of shoe 16 and by a clip 26 slidable on its end it supports the right end of shoe 16,—i. e. outward movement of shoe 16 acts through clip 26 to distort spring 24 crosswise. At its left end, spring 24 is directly connected to the lower end of shoe 18, and a second clip 28 serves to support the left end of shoe 16. A second spring 30 is directly connected at its lower end to the left end of shoe 16, while its upper end is connected directly to the upper end of shoe 18, and by a clip 32 is also connected to the upper end of shoe 14.
- 45 Shoe 14 is applied by a lever 34 mounted
- 50 at its lower end on a pivot 36 carried by backing plate 12, and preferably having a roller or other part 38 having rolling engagement with the shoe approximately at its center.
- 55 Shoe 18 is applied by a lever 40, preferably having a roller or other part 42 having rolling engagement with the shoe approximately at its center, and which is mounted on a pivot 44 carried by the backing plate.
- 60 Lever 40 has a part 46 extending beyond pivot 44, and operatively engaging the end of a third lever 48 pivoted between its ends at 50, and preferably having at its end a roller or other part 52 having rolling engagement 70 with shoe 16 approximately at its center.
- 65 It will be seen that all three shoes are applied by forcing apart the upper ends of the pair of levers 34 and 40. For this purpose I provide a novel cam or expanding device 75 54, integral with or secured to the usual cam-shaft. This device has one projection 56 extending between the ends of the levers and serving as a cam acting on lever 40 to apply shoe 18 (and 16), and a second projection 80 58 on the opposite side of the end of lever 34 and serving as a cam acting on that lever to apply shoe 14. The two projections define a notch receiving the end of lever 34.
- 70 While one illustrative embodiment has 85 been described in detail, it is not my intention to limit the scope of the invention to that particular embodiment, or otherwise than by the terms of the appended claims.

I claim:

1. A brake comprising, in combination, a drum, at least three shoes arranged end to end within the drum, a pair of levers arranged to be forced apart to apply two of the shoes, and a third lever operated by one of said pair of levers and arranged to apply the third shoe.
2. A brake comprising, in combination, a drum, at least three shoes arranged end to end within the drum, a pair of levers pivoted near their ends and arranged to be forced apart to apply two of the shoes and one of which has a part extending beyond its pivot, and a third lever operated by said part and arranged to apply the third shoe.
3. A brake comprising, in combination, a drum, at least three shoes arranged end to end within the drum, a pair of levers pivoted near their ends and arranged to be forced apart to apply two of the shoes and one of

- which has a part extending beyond its pivot, and a third lever pivoted between its ends and engaging said part at one end and the third shoe at the other end.
4. A brake comprising, in combination, a drum, friction means engageable with the drum, a pair of levers having rollers between their ends which act on the friction means, a third lever operatively engaged by one of the pair of levers and which also has a roller acting on the friction means, and means for forcing the pair of levers in opposite directions to cause the three rollers to force the friction means against the drum.
5. A brake comprising, in combination, a drum, friction means engageable with the drum, a pair of levers having parts which act on the friction means, a third lever operatively engaged by one of the pair of levers and which also has a part acting on the friction means, and means for forcing the pair of levers in opposite directions to cause the three said parts to force the friction means against the drum.
6. A brake comprising, in combination, a drum, a plurality of unconnected floating segmental shoes arranged end to end within the drum and each of which has at each end a double-wedge recess facing toward the center of the drum, a part in each recess to take the braking torque and at the same time to wedge the shoe against the drum, and a corresponding plurality of interconnected levers acting on the three shoes approximately at their centers to force them against the drum.
7. Brake-applying means comprising, in combination, a pair of pivoted parts having their free ends adjacent each other, and a rotatable applying device between said ends having a projection extending between said ends and serving as a cam acting one one of said ends and having a second projection on the opposite side of the other of said ends and acting as a cam thereagainst, the two projections defining a notch in which said other end is received.
8. A brake comprising, in combination, friction means, a plurality of levers acting on angularly-spaced parts of the friction means to apply the brake, and driver-controlled means for operating at least one of the levers, at least one of the other levers being arranged to be operated solely by said one of the levers.
9. Brake-applying means for a brake having a drum, comprising a lever arranged within the drum and fulcrumed between its ends, operating means at one end of said lever, a brake-applying part between said means and the fulcrum of the lever, and another lever having another brake-applying part and which is operated by the first lever.
10. A brake comprising, in combination, a drum, a plurality of unconnected floating segmental shoes arranged end to end within the drum, and a plurality of operating devices, one for each shoe, at least one of which devices is operated solely by one of the other devices.
11. A brake comprising, in combination, a drum, a plurality of shoes arranged end to end within the drum, and a plurality of operating devices, one for each shoe, at least one of which devices is operated solely by one of the other devices.

In testimony whereof, I have hereunto signed my name.

HOWARD M. LEONARD.
